UNITED STATES PATENT OFFICE

MAX PINKERT, OF PFORZHEIM, AND IMANUEL MÜLLER, OF NEUENBURG, GERMANY;
SAID PINKERT ASSIGNOR TO SAID MÜLLER

SEAL

Application filed April 24, 1928, Serial No. 272,428, and in Germany August 10, 1927.

The present invention has reference to metal seals for sealing all kinds of containers, goods in transit, railroad cars, and the like and it relates more specifically to a sheet 5 metal seal, commonly called "lead", comprising a housing and a flexible metal loop or strap, the two ends of which are superimposedly secured within the housing, the device then forming a closure which can be 10 opened again only by forcibly breaking the parts.

Seals of this particularly type, in which the two strap ends are inter-engagingly clamped when the seal is closed, are substantially of two kinds. In the one kind the free strap end is of the same cross-section as the rest of the strap, that is to say extends in a straight plane, and the other kind has a tubular strap end. The flat strap end lacks rigidity necessary for quick and ready insertion into the housing, and both types can readily be tampered with and can be opened and closed again by a skilled hand without outwardly showing any damage.

25 In the flat-ended type, the closed seal can readily be opened by shoving back the barbed strap end sufficiently to move the barbs away from the stop members on the housing or the other strap end and by then inserting a strip 30 of sheet metal and thereby depressing the barbs and keeping them depressed during the withdrawal of the strap end from the housing.

In the tubular strap end type the barbs are 35 struck out from the tube wall and snap into corresponding perforations of the other, also tubular strap end. By relatively displacing these tubular members, or by introducing one or two half-tubes between the two nested tubular strap ends it is relatively easy to 40 open and close these seals without outward showing of such tampering.

A further disadvantage of the well known 45 sheet metal leads of this character is that the relatively thin metal parts do not allow the impressing of names, dates, or other designations, at least not with the conventional sealing tools now used by railroad employees 50 and other carriers.

The present invention does away with all these disadvantages.

The invention essentially resides in the stiffened conformation of the strap end to be closely inserted into the housing, obtained by tooling the end portion to present a grooved or channeled cross-section, and in the formation of hooks or barbs near the extremity of this strap end for hooking cooperation with the other strap end within the two-part housing. The stiffened strap end thus is not tubular in cross-section, but trough-shaped, the two trough or channel edges in the closed position of the seal structure preventing a relative rotary or twisting 60 displacement of the strap ends. The unique arrangement and operative engagement of the barbs with the other strap end make the insertion of a metal strip or tool impossible and thus make the seal proof against tampering. 70

In order to make our invention more readily understood, we will now describe it in detail in connection with the accompanying drawings, in which Fig. 1 is a side elevation 75 of the strap end which is normally retained in the seal housing; Fig. 2 is a top view thereof, and Fig. 3 a cross-section therethrough on line 3—3 of Fig. 2. Figs. 4, 5 and 6 illustrate side elevation, top view, and cross-section on line 6—6 of Fig. 4 respectively, of the reinforced, barbed other end of the loop or strap. Fig. 7 is a longitudinal section, and Fig. 8 a top view of the seal housing. Fig. 9 is a longitudinal section, and Fig. 10 a 80 top view of the housing cover. Fig. 11 is a top view of the closed seal with part of the strap broken away. Fig. 12 is a longitudinal section through the closed seal. Fig. 13 is a fragmentary vertical section through a constructional modification. Fig. 14 is a longitudinal section, and Fig. 15 the top view of a modified construction of the reinforced strap end. 85

The end of the loop or strap *a*, of flexible 95 metal, to be placed around or through the object to be sealed or "leaded", is machined at the one end to form a stiffened, troughed or channeled structure *b*, and at its other end, which normally is always retained within 100

the housing, the strap presents the flat tongue *c*. Near the extremity of the free end *b* are provided laterally flaring hooks or barbs *e* (Figs. 4 and 5), or, as in the modification illustrated in Figs. 14 and 15, barbs or spurs *e'* are struck out from the channel bottom and are turned through an angle of 90 degrees downwardly, forming with the respective channel walls an angle *d*. The tongue member *c* is positioned in the housing *g* so that the struck-up eye nipple *h* passes through the cut-out *i* in the tongue member *c*, and the raised wall portion *k* engages in the trough-shaped keeper sleeve or member *f*, closing the latter's open side, and also forming a support for the outer edges of the channeled strap end to prevent the latter from becoming relatively twisted.

In the embodiment according to Figs. 4 and 5, the splayed barbs *e* extend in the same plane with the outer channel edges, so that this alone would already prevent a twisting movement of the strap end *b* within the seal housing.

25 The cover member *l* (Figs. 9 and 10) closes the housing, the dome portion *m*, which is open toward the strap passage, enclosing the keeper *f*, and the cover is held in place by the edge of the housing *g* being crimped or 30 turned over as shown in Fig. 12. The cover *l* is provided with a perforation *o* for the passage of the eye-nipple *h*. A lead rivet *p* is secured in this eye *h* by a short lateral extension *q*, and markings may be recorded in 35 this lead filling in the usual manner. In Fig. 13 this lead closure is shown as caught under the turned over housing edge *n*, for additional security against tampering or loosening.

40 In closing the seal the end *a* is slidably inserted through the trough shaped keeper *f* via the inner exposed end of said keeper and until the barbs *e*, which are pressed inwardly close to the walls of the channel *b* by the walls 45 of the keeper, pass the outer end of the keeper into a chamber formed by the wider portion of the housing *g*, said barbs then springing outwardly so as to hook over the sides of the keeper at its outer end and lie 50 in the contracted space between the same and the housing and adjacent to the contracted inner portion of the housing, whereby the barbed end of the end *a* is enclosed in the said chamber and interlocked therein with the keeper in such a manner that the barbs 55 cannot be tampered with or released without disruption of the seal.

For opening the seal the strap must be 60 severed. In order to readily break the strap by manually bending it to and fro, there are provided two opposed notches *r* at a plane falling just within the housing wall when the strap end is shoved home in the housing. 65 A stiffening and positioning bead *s* is pressed

out of the strap *a*, the housing wall *n* lying between this bead *s* and the notches *r*.

In the embodiment shown in Figs. 14 and 15 the stiffened strap end *b* extends over the trough *f*, the inwardly directed barbs *e'* hooking over it from within outwardly.

What we claim is:—

1. A seal comprising a metallic strip having a catch end and a keeper end, adapted for interlocking engagement, the keeper end being provided with a keeper member and a casing substantially enclosing the same, the keeper member comprising two parts, one having an opening and the other a nipple projecting through said opening, and a body of material engaging the member having the opening and extending through the nipple of the other member and interconnecting said members.

2. A seal of the character described comprising a metallic strip having a catch end formed with a channeled portion the walls of which are formed with lateral barbs and a keeper end to receive said catch end, said keeper end carrying a keeper member having a contracted inner end portion and an expanded outer end portion, said keeper member being adapted to receive the channeled end of the catch and the barbs of the latter being adapted for interlocking engagement with the outer end of the keeper member.

In testimony whereof we have signed our names to this specification.

MAX PINKERT.

IMANUEL MÜLLER.
